His ATTORNEY.

UNITED STATES PATENT OFFICE.

CHARLES D. BENNETT, OF ELIZABETHTOWN, INDIANA.

RAILWAY.

SPECIFICATION forming part of Letters Patent No. 635,526, dated October 24, 1899.

Application filed April 10, 1899. Serial No. 712,444. (No model.)

To all whom it may concern:

Be it known that I, CHARLES D. BENNETT, of Elizabethtown, county of Bartholomew, and State of Indiana, have invented a certain new and useful Improvement in Railways; and I do hereby declare that the following is a full, clear, and exact description thereof, reference being had to the accompanying drawings, in which like figures refer to like parts.

10 The object of this invention is to make a practical metal tie for railways, one that will perform the service desired and yet be easy and cheap to make and manipulate.

Another object is to provide a safe and 15 practical means for spiking the rail to the ties.

Another feature is to provide with the ties metal stringers for rigidly supporting the rails at the joints, whereby the joints cannot be de- 20 pressed.

Still another object is the combination, with these parts, of a nut-locking plate.

The various features of my invention will be more fully understood from the accompanying drawings and the description and claims 25 following.

In the drawings, Figure 1 is a perspective of the parts of the railway in place, parts being broken away, as shown. Fig. 2 is a plan 30 of a portion of a rail and tie where the rail crosses the latter. Fig. 3 is a cross-section of the tie with the end of a girder connected therewith and being an inside elevation. Fig. 4 is a detail of a spike, the split ends being shown in dotted lines bent upward. Fig. 5 35 is a central horizontal cross-section of a part of the two ties and all of the connecting-stringer. Fig. 6 is a cross-section of the upper part of a tie and nut-lock with the spike 40 in place.

In detail I make the cross-ties 1 in substantially the form of inverted-T beams, comprising a wide lower part or flange and narrow top or flange with a centrally-connecting web.

45 The wide bottom rests on the road-bed. The top is about four and one-half inches in width. Centrally through the top of the cross-tie I make a spike-hole 2, that bifurcates after it reaches the web and extends on each side 50 thereof. The spike 3 is much like the ordinary spike, excepting its head is wider and its stem is split nearly to its head and in line par-

allel with the extension of the head that overlaps the flange of the rail 4. The spike is inserted into the spike-hole 2 and the two parts of 55 the stem separated and turned upward around the flanges of the top of the cross-tie and across the top of the tie until the extreme ends extend under the sides of the spike-head bearing against the flange of the rail. The head of 60 the spike is then driven to its limit. The head has in addition to the lateral projection over the flange of the rail the side extensions 15, that rest upon the ends of the spike, and lower shoulders 16, that rest upon the tie or 65 fish-plate. Thus the ends of the spike are held down. This construction of railway will hold the rails securely in place. The spikes are withdrawn by claw-bars in the ordinary 70 way after the ends are loosened and turned back and down; but at other times their hold on the tie is extremely strong, even stronger than in wood ties.

At joints of the rails I connect the ties with 75 stringers 5, preferably formed, like the ties, in cross-section. The ends 6 are turned side-wise, as shown in Fig. 5, and secured to the webs of the ties by the bolts 7. The lower flange or base of the girders is provided at each end with a lap 17, that rests upon the 80 base of the tie. This gives the girder a firm base-support. With this support of the rails at their joints they will not yield to the strain, as is the case with wooden ties. The abutting ends of the rails are connected by the fish- 85 plates 8 and the bolts 9. A nut-locking plate 10 is provided, shaped so as to fit snugly on the fish-plate and provided with notches 11 of such shape as to fit snugly about the nuts on said bolts 9. Said plate 10 has where it 90 crosses the tie an extension 12, through which the spike 3 extends and upon which the ends of the parts of the stem of the spike are bent downward, as shown in Fig. 1. Where the parts of the spike-stem are turned up about 95 said plate 12, as well as the top of the tie, notches 13 are provided. These notches 13 are of great value in resisting lateral movement of the ends of the spike, and thereby holding the rail more positively in place. The 100 nut-locking plate 10 is put in place after the nuts are secured on the bolts 9. These nuts cannot be removed, therefore, until said plate 10 has been removed. The plate 10 is also to

strengthen the joint of the rails and the means for holding them in place on the cross-ties.

What I claim as my invention, and desire to secure by Letters Patent, is—

- 5 1. A metallic cross-tie for railways whose shape is substantially that of an inverted-T beam with a flat top or head, and a spike-hole extending centrally through the top of the beam and bifurcating to each side of the web 10 of the tie.
- 15 2. In a railway, the combination with the rail, of a metallic cross-tie whose shape is substantially that of an inverted-T beam with a flat top or head being provided with spike-holes extending centrally through the top of the beam that bifurcate to each side of the web, and a spike with a split stem whose parts 20 extend through the spike-hole and are bent up about the flanges of the top of the tie beside the rail.
- 25 3. In a railway, metallic cross-ties substantially in the shape of an inverted-T beam with a flat top or head with spike-holes extending centrally through the top of the beam and bifurcating to each side of the web and notches 30 in the edges of the top of the tie beside the spike-holes, suitable rails, and spikes with their stems split and extending through the spike-holes and turned up and fitting in the notches in the top of the tie and down upon the top of the ties beside the rails.
- 35 4. In a railway, a metallic cross-tie for railways whose shape is substantially that of an

inverted-T beam with a flat top or head and a spike-hole extending centrally through the top of the beam and bifurcating to each side of the web of the tie, and a spike with the head adapted to overlap the flange of the rail and having side extensions and shoulders below said extensions to rest upon the tie the parts of 40 the spike being long enough to extend around the flanges of the top of the tie and abut against the spike immediately under the head.

5. In a railway, suitable rails, metallic cross-ties whose shape is substantially that of an inverted-T beam with a flat top or head and provided with spike-holes extending centrally through the top and bifurcating to each side of the web and also notches in the flanges of the top opposite said spike-holes, fish-plates, 45 bolts and nuts for securing the ends of the rails together and a nut-locking plate fitting on said fish-plate and having notches to partially surround said ends and prevent their turning, and a flange extending from said plate and resting upon the tie, said flanges 50 having notches in its sides that register with the notches in the top of the tie.

In witness whereof I have hereunto affixed my signature in the presence of the witnesses 55 herein named.

CHARLES D. BENNETT.
